UNITED STATES PATENT OFFICE

PHILIP H. CHRISTOPHER, OF FAIRMONT, WEST VIRGINIA

COMBINATION REFRIGERATOR AND SHOW CASE

Application filed March 25, 1929. Serial No. 349,667.

The present invention relates to improvements in refrigerators and has reference more particularly to a combination refrigerator and display show case.

5 One of the important objects of the present invention is to provide a combination refrigerator and show case wherein the show case is divided into a central refrigerating chamber and end refrigerant compartments
10 or chambers, a removable refrigerant container being arranged within the refrigerating chamber and being provided with air circulating tubes which when the door to the refrigerating chamber is open act as air
15 ventilators.

Another important object of the invention is to provide a combination refrigerator and display show case wherein a series of spaced horizontally arranged rollers are mounted 20 in the bottom of the central refrigerating chamber and on which rollers is movable the refrigerant container whereby the latter may be moved into and out of the compartment without any difficulty, additional 25 means being provided for supporting the refrigerant container when the latter is moved entirely out of the refrigerating compartment or chamber provided therefor in the show case.

30 A still further object is to provide a combination refrigerator and show case wherein the bottom portion as well as the rear side of the show case is constructed with suitable insulation, additional means being provided
35 for draining off the water that drips from the refrigerant container.

Another object is to provide a combination refrigerator and show case of the above-mentioned character wherein suitable ventilators are arranged at the front and rear sides below the floor portion of the show case.

A still further object is to provide a structure of the above-mentioned character which is simple, inexpensive, strong and durable.

Other objects and advantages of the invention will become apparent from the following description when taken in connection with the accompanying drawings.

50. In the accompanying drawings wherein

like reference characters indicate corresponding parts throughout the same;

Figure 1 is a rear elevation of the combination refrigerator and show case embodying my invention.

Figure 2 is a front elevation thereof.

Figure 3 is an enlarged vertical sectional view through the refrigerating chamber showing the refrigerant container arranged therein, parts being broken away.

Figure 4 is a longitudinal vertical section through the refrigerator and show case for more clearly disclosing the horizontally disposed air tubes arranged in the refrigerant container; and

Figure 5 is a fragmentary perspective view of one of the rollers.

In the drawings wherein for the purpose of illustration is shown the preferred embodiment of my invention, the numeral 1 designates generally the combination refrigerator and show case. The base of the show case is designated by the reference character 2 and the flooring for the show case is arranged on the base in such a manner as to be spaced from the ground as clearly indicated in Figures 3 and 4. Suitable screened ventilating openings 3 are formed at the front and rear sides of the base 2 as more clearly disclosed in Figures 1 and 2 of the drawings. The flooring includes a wooden surface 4 the upper face of which is covered with sheet metal denoted by the reference character 5. A wooden sub-flooring 6 is arranged in spaced relation below the main flooring 4 and suitable insulating material such as cork 7 fills the space between the main and sub-floorings 4 and 6. Two layers of heavy waterproof paper 8 is arranged on the upper face of the sub-flooring 6.

The rear wall of the show case is shown generally at 9 and the same includes spaced wooden panels 10 the outer faces of which are covered with sheet metal as indicated at 95 11 while layers of paper 12 are arranged adjacent the inner faces of the wooden panels and suitable insulating material such as cork 13 fills the space between the wooden panels. It is of course to be understood that suitable 100

spacing blocks 14 are interposed between the wooden panels.

The front wall of the show case includes a wooden frame 15 in which is arranged the 5 glass panels 16. Additional glass panels 17 are also arranged in the frame 15 rearwardly of the foremost glass panels 16 and a dead air space 18 is arranged between the panels 16 and 17. Additional glass panels 19 are 10 arranged in the rear portion of the frame and in spaced relation with respect to the intermediate glass panels 17 to form the dead air spaces 20.

The top of the show case is shown at 21 15 and the same is formed with suitable openings in the end portions thereof to accommodate the beveled plate glass 22. A felt packing is arranged beneath the edges of the plate glass 22. A glass panel 23 is arranged in the 20 top 21 beneath the glass panels 22 and a dead air space 24 is provided between the spaced glass panels 22 and 23 as more clearly suggested in Figure 3.

The end walls of the show case are designated by the numeral 25 and are constructed in the same manner as the rear wall 9 and therefore a detailed description of the end walls is believed unnecessary.

The show case or refrigerator 1 is divided 30 into what I term a central refrigerating compartment or chamber 26 and the end refrigerant compartments or chambers at 27. Access to these compartments are had through suitable openings provided in the rear wall 35 9 and a door 28 provides a closure for each of the openings in the refrigerant compartments 27. A door 29 provides a closure for the openings in the rear side of the refrigerating compartment 26.

40 Suitable bars 30 extend horizontally in the rear portion of each of the refrigerant compartments 27 and coacting therewith is the angle iron bar 31 that extends horizontally across the front side of the refrigerant compartments as well as the refrigerating compartment or chamber. The bars provide a means for supporting suitable meat racks or trays in the refrigerant compartments and the portion of the angle iron bar 31 that extends across the front of the refrigerating chamber or compartment 26 constitutes a stop for the movable refrigerant container 32, the construction of which will be specifically described later in the specification.

45 A pair of angle iron rails 33 extend from the front to the rear of the central refrigerating chamber or compartment 26 adjacent the bottom thereof, and suitable elongated tubular rollers 34 are mounted for rotation on 50 suitable elongated bolts 35 that extend through the upstanding sides of the pair of spaced angle iron rails 33. A drip pan 36 is supported below the angle iron rails 33 and a discharge pipe 37 extends from the bottom of this drip pan into the funnel-

shaped upper end of a drain pipe 38 that projects downwardly through the floor and the base of the show case in the manner as clearly shown in Figure 3. This drip pan catches the drippings from the refrigerant container 70 32 so that the same will not collect on the floor of the refrigerator.

The refrigerant container is open at its upper end and the front wall thereof is inclined to conform to the angular disposition of the front wall of the show case. A removable cover or lid 39 is provided for the open upper end of the metallic container 32. A pair of independent horizontally extending air circulating tubes 40 are arranged through registering openings formed in the opposite sides of the container. These air tubes may however be formed integrally with the container.

75 The container 32 rests on the horizontally disposed rollers 34 and attached to the rear side of this container is a hinged supporting leg 41 which is normally swung upwardly against the rear side of the container when the latter is disposed within the compartment 26. When the door 29 is swung to an open position, the container 32 may be moved outwardly of the compartment 26 with only the forward portion of the container extending within the compartment. The hinged leg 41 is then swung downwardly to the position shown in the dotted lines in Figure 3 whereby to support the container in a horizontal position. The container is preferably 80 adapted to contain a quantity of brine or ice 100 which is used as the cooling medium.

85 The purpose of the tubes 40 is to provide a means whereby when the refrigerator door is open, said air tubes will act as air circulators thereby keeping cold air continuously passing through the refrigerant compartments 27. If desired, any electrical or mechanical refrigerating machine may be employed in conjunction with my improved show case.

90 A combination refrigerator and show case 105 of the above mentioned character can be constructed at a very low cost and the same will at all times be positive and efficient in carrying out the purposes for which it is designed.

95 While I have shown the preferred embodiment of my invention, it is to be understood that minor changes in the size, shape and arrangement of parts may be resorted to without departing from the spirit of the invention or the scope of the appended claims.

100 What I claim is:

1. In a refrigerator show case of the class described, a refrigerating compartment, a food compartment having communication with the refrigerating compartment, the rear side of each compartment being provided with a doorway, a door therefor, a plurality of spaced rollers arranged horizontally in the bottom of the refrigerating compartment, and a refrigerant container mounted for 115 120 125 130

movement into and out of the refrigerating compartment through the doorway on said rollers.

2. In a refrigerator show case of the class described, a refrigerating compartment, a food compartment having communication with the refrigerating compartment, the rear side of each compartment being provided with a doorway, a door therefor, a plurality of 5 spaced rollers arranged horizontally in the bottom of the refrigerating compartment, and a refrigerant container mounted for movement into and out of the refrigerating compartment through the doorway on said 10 rollers, and a vertically swinging leg attached to the rear side of the refrigerant container and adapted to swing downwardly to engage with the floor to support the outer end portion of the container when the latter is partly 15 moved out of the refrigerating chamber.

3. In a refrigerator show case of the class described, a refrigerating compartment, a food compartment having communication with the refrigerating compartment, the rear 20 side of each compartment being provided with a doorway, a door therefor, a plurality of spaced rollers arranged horizontally in the bottom of the refrigerating compartment, and a refrigerant container mounted for movement into and out of the refrigerating compartment through the doorway on said 25 rollers, and angle iron rails extending between the front and rear sides of the refrigerating compartment and between which the lower 30 portion of the refrigerant container is movable, the rollers being arranged between the upstanding walls of the angle iron rails.

In testimony whereof I affix my signature.
PHILIP H. CHRISTOPHER.
